IGNITION SYSTEM

Alfred Aubyn Linsell, London, England, assignor
to Radio Corporation of America, a corporation
of Delaware

Application September 13, 1935, Serial No. 40,364
In Great Britain September 15, 1934

2 Claims. (Cl. 123—148)

This invention relates to systems and apparatus for obviating disturbances in radio receivers by the ignition systems of nearby internal combustion engines and has for its object to provide simple efficient and easily installed apparatus whereby the ignition systems of the internal combustion engines of motor cars, aeroplanes, and so forth, may be modified without serious constructional alteration or serious interference with their main purpose as ignition systems in such manner as to reduce or substantially eliminate their interference with nearby radio receivers used on such vehicles.

The problem of interference with radio receivers by the ignition systems of internal combustion engines is a well known and serious problem which becomes very pressing in the case of aircraft and motor cars, and various expedients have been proposed to modify ignition systems so as to reduce or substantially eliminate such interference. Among the expedients already proposed are the screening of those parts of the ignition system likely to cause interfering radiation, another being the provision in series in the leads to the sparking plugs and any other ignition leads (if any) likely to give rise to interfering radiation, of damping resistances designed and intended to damp out disturbing radiation-causing oscillations.

The principal objection to the first of the above mentioned expedients is the considerable amount of structural alteration which is generally involved if complete screening is to be obtained, while the second expedient as utilized in known anti-interference ignition systems of the kind wherein damping resistances are inserted, suffers from the disadvantage that the resistances must be fairly expensive if they are to withstand the considerable voltage peaks to which they are subjected while, furthermore, they introduce of necessity resistance losses which may quite seriously reduce the effectiveness and efficiency of the ignition system as such.

The present invention provides improved means for reducing and substantially preventing the back surge of current which tends to occur in an ignition system after sparking has occurred therein, and according to this invention one or more high frequency rectifiers is or are inserted in series in the lead or leads to those parts of an ignition system where sparks occur when the system is functioning. The rectifier or rectifiers must, of course, be connected in such sense as to allow the initial flow of current to the sparking

points to occur but to prevent the subsequent back surge.

The invention is illustrated in the accompanying diagrammatic drawing which shows one way of carrying it into effect.

Referring to the drawing each of the ignition leads leading from the distributor points of the distributor of an internal combustion ignition system to the sparking plugs of the engine includes in series therewith a plurality of high frequency rectifiers such as copper oxide rectifiers. In the drawing the distributor of the engine ignition system is represented at D and the distributor points at $d_1d_2d_3d_4$ only two leads L from the points to the sparking plugs SP being shown. Preferably there are at least two such rectifiers R1R2 in each lead from a distributor point to a sparking plug terminal, one rectifier being adjacent the distributor point and as close to it as possible and the other being adjacent the sparking plug terminal and as close to that as possible.

If the rectifiers are connected in correct sense current flow in the direction to occasion sparks at the sparking plugs will not be reduced to any substantial extent, but back surge from the sparking plugs will be substantially prevented owing to the unilateral conducting properties of the rectifiers. It is, of course, theoretically possible to use electron discharge rectifiers in place of crystal or chemical rectifiers—e. g., in place of the copper oxide rectifiers already referred to—but in general, electron discharge rectifiers are not preferred from the practical point of view for obvious reasons, principally concerned with installation maintenance and operating costs. It is also possible in some cases to use thermionic rectifiers e. g. diodes having low temperature emitting cathodes, and in some cases heat from the engine, e. g., conducted from the central stem of a sparking plug might be used to assist or cause such a cathode to become electron emissive. As above stated, however, the use of electron discharge rectifiers is not preferred owing to the cost and comparative complication involved.

Of course, where an electron discharge device is utilized in carrying out this invention means should be provided for short circuiting it when starting the engine, and if desired, such short circuiting means may be provided in association with any form of rectifier used in carrying out this invention. Any convenient means may be provided for short circuiting the rectifier or rectifiers while starting the engine; for example any short circuiting expedients or arrangements

as described in my application Serial No. 20,900, filed May 11, 1935, may be employed. Such a system is diagrammatically shown as comprising a switch S and leads 10 and 11.

Although the invention provides an interference suppressor system whereby a high degree of suppression is obtainable without the use of screening means or resistances interposed in ignition leads, the said invention is obviously not limited in its application to systems wherein no such screening means or interposed resistances are provided but can be used in conjunction with the known expedients of using suppressor resistances and/or inductances and/or screening. When, however, the said invention is so used in conjunction with the said known expedients, the suppressor resistances and/or inductances may be

made of lower value than would be the case where they provided as the only means of interference suppression while similarly less extensive screening can be employed.

Having described my invention, what I claim 5 as new and desire to secure by Letters Patent is:

1. An engine ignition system comprising a spark plug, a high tension voltage source and a connection between said spark plug and voltage source excluding a crystal rectifier arranged to 10 substantially prevent currents of high frequency from passing from said spark plug to said voltage source.

2. The combination defined in the preceding claim in which said rectifier is of the copper oxide 15 type.

ALFRED AUBYN LINSELL.
